UNITED STATES PATENT OFFICE.

LEO F. ADT, OF ALBANY, NEW YORK.

NOSE-GUARD FOR EYEGLASSES.

1,003,685.

Specification of Letters Patent. Patented Sept. 19, 1911.

Application filed March 24, 1906. Serial No. 307,775.

To all whom it may concern:

Be it known that I, LEO F. ADT, of Albany, in the county of Albany and State of New York, have invented certain new and useful Improvements in Nose-Guards for Eyeglasses; and I do hereby declare the following to be a full, clear, and exact description of the same, reference being had to the accompanying drawings, forming a part of this specification, and to the reference-numerals marked thereon.

My present invention relates to improvements in eyeglasses, and the object of the invention is to provide improved nose-guards that are so constructed and attached to the mounting as will enable them always to adjust or adapt themselves automatically to the shape of the wearer's nose, so that the necessity of previously bending and twisting the guards in order to fit them to the nose is obviated.

To these and other ends the invention consists in certain improvements and combinations of parts, all as will be hereinafter more fully explained, the novel features being pointed out in the claims at the end of the specification.

In the drawings: Figure 1 is a perspective view of a pair of eyeglasses having nose guards constructed in accordance with my invention, one of the lenses being omitted. Fig. 2 is a perspective view of the nose-guard removed from the mounting. Figs. 3 and 4 are perspective views showing the nose-engaging portion, and the attaching arm separately. Fig. 5 is a rear elevation of one of the nose guards shown in Fig. 1, the full and dotted lines indicating the range of movement of the guard in a vertical plane. Figs. 6 and 7 are top plan views of the guard, showing the angle of adjustment thereof in substantially a horizontal plane. Fig. 8 is a perspective view of the nose-engaging portion of the guard applied to a different form of attaching arm, and Figs. 9 and 10 are perspective views of the nose-engaging portion and the attaching arm separately.

Similar reference numerals in the several figures indicate similar parts.

The nose guards shown in the present embodiments of my invention are self-adjusting in two directions in order that they may accommodate themselves to the horizontal angle or taper toward the front of the nose, as well as the vertical slant or angle

formed by the sides of the nose, and referring particularly to the form shown in Figs. 1 to 7 inclusive, 1 designates the bridge or spring, having its ends connected to the ordinary lens-attaching devices 2 and 3, by any suitable means, such as the well known fastening screw 4, the attaching devices being secured by suitable means to the lenses, one of the lenses 5 being shown in Fig. 1.

The nose guards embodying my invention each comprise an attaching arm 6, having in the forms shown an upturned attaching lug 7 adapted to be secured to the attaching device by the screw 4, a portion of the guard-attaching arm being provided, in the forms shown in Figs. 1-7 inclusive, with a pair of transverse slots 8 and 9 having a strip of the material 10 separating them. The nose-engaging portion of the guards herein shown is of simple form, comprising a body portion having upper and lower nose-engaging pads or surfaces 11 and 12 approximately conforming to the surface at the side of the average nose, and the intermediate or connecting portion of the guard is preferably narrowed and provided with a pair of arms 13 and 14 extending preferably in rear of the nose-engaging portion of the guard, these arms 13 and 14 being adapted to rest in the slots 8 and 9 respectively of the attaching arm and arranged to embrace the strip of material 10. These arms are preferably formed of flat material and stamped in one piece with the nose-engaging portion of the guard, and are of sufficient width and fit closely against the ends of the respective slots 8 and 9 as will prevent a relatively forward and rearward tilting motion of the guard, so that the angle of rearward inclination of the guards will remain constant when once adjusted to conform to the rearward slant of the nose. However, those portions of the arms 13 and 14 resting in rear of the portion 10 are sufficiently loose to permit a rocking movement of the nose-engaging portion on an axis transverse to the plane of the lenses, as illustrated in Fig. 5, so that when the guard is brought into engagement with the nose, it will automatically adjust itself to the vertical angle of the side of the nose, while the space between the ends of the arms 13 and 14 and the rear surface of the nose-engaging portion of the guard provides a loose fit between them and the portion 10 of the attaching arm that will permit a

limited amount of relative swinging movement between the guard-attaching arm and the nose-engaging portion on a vertical axis, and this adjustment allows the nose-engaging portions to adapt themselves to the forward taper of the nose, as indicated in Figs. 6 and 7.

Instead of employing an attaching arm of the kind shown in Figs. 1-7 inclusive, arms of different forms may be employed, the arms shown in Figs. 8 and 10 embodying an attaching lug 15 adapted to the lens-attaching device, having a rearwardly-extending portion 16, the latter having the upwardly and downwardly-turned arms 17 and 18 proceeding from its opposite edges and adapted to enter the space between the arms 13 and 14 and the rear side of the nose-engaging portion, the sides of the arms of the guard-attaching arm and of the nose-engaging portion fitting sufficiently loose to permit the latter a rocking movement to enable it to accommodate itself to the more or less irregular surface at the side of the nose, while the edges of the material composing the arms of one part fit sufficiently close to the bends in the coöperating arms of the other part as will prevent a swinging movement of the guards in a plane transversely of the lenses, and consequently the angle of rearward inclination of the guards will be preserved.

Nose guards constructed in accordance with my present invention do not require the usual operation of bending and twisting by the optician in order that they may conform to the nose of each individual, as the nose-engaging portions of the pads receive the pressure at intermediate points and adjust themselves to the different angles and to the irregular surfaces of different noses, so that an even or uniform pressure is produced on the nose throughout the surface engaged by the guards, thereby avoiding undue pinching, and insuring a firm hold of the eyeglasses on the nose, without requiring a special adjustment of the guards for each individual.

Guards embodying my invention are particularly efficient when employed in connection with eyeglasses having a spring bridge, the action of which produces pressure on the guards for holding them against the nose, and the particular embodiments shown illustrate the guards as used in such connection, but it will be understood that nose guards embodying my invention may be used to advantage on spectacles, or eyeglasses having rigid bridges wherein the requisite pressure for holding the guards against the wearer's nose is supplied by separate springs or from other sources.

The specific forms of the invention shown are also punched and formed from sheet material and consequently are easily and

cheaply manufactured, but it will be understood that the invention is not limited to these specific embodiments, and that the guard-attaching arms may be appropriately formed to enable them to be attached to 70 mountings of different styles.

I claim as my invention:

1. An eyeglass guard comprising a rearwardly extending supporting arm provided with a bearing portion embodying substantially parallel opposite edges and a nose engaging portion extending above and below the rearwardly extending arm and having a pair of spaced arms provided with substantially parallel faces extended around and 80 loosely engaging said edges to rock to limited extent longitudinally thereof and to also permit the nose engaging portion to turn to a limited extent laterally about the same. 85

2. An eyeglass guard comprising a rearwardly extending supporting arm provided with a flat bearing portion embodying substantially parallel opposite edges, and a nose engaging portion composed of sheet material 90 extending above and below the arm and having a pair of spaced substantially parallel flat arms extended around said edges to rock to a limited extent longitudinally thereof and to also turn to a limited extent laterally 95 about the same, the extremities of the arms being turned against one face of the flat bearing portion, while the nose engaging portion rides loosely against the opposite face. 100

3. An eyeglass guard comprising a rearwardly extending supporting arm provided with a flat bearing portion embodying substantially parallel opposite edges terminating in limiting shoulders and a nose 105 engaging portion composed of sheet material extending above and below the arm and having a pair of spaced substantially parallel flat arms extended around said edges between the shoulders to rock to a limited extent longitudinally thereof and to also turn to a limited extent laterally about the same, the extremities of the arms being turned against one face of the flat bearing portion 110 while the nose engaging portion rides loosely 115 against the opposite face.

4. In eyeglasses, the combination with the lenses, and a bridge connected to them, of nose guards each embodying a substantially vertically-extending nose-engaging portion 120 having a pair of flat arms extending substantially in parallelism from its lateral edges and doubled behind the said portion, and a rearwardly-extending attaching arm having a vertically-disposed bearing portion 125 having substantially parallel opposite edges loosely resting between and against the doubled portion of the said arms on the one side and the body of the nose-engaging portion on the other. 130

5. In eyeglasses, the combination with the lenses, and a bridge connected to them, of nose guards each embodying a nose-engaging portion having a pair of connecting arms, and an attaching arm having slots therein to loosely receive the arms of the nose-engaging portion, a strip of material between the slots serving to hold the nose-engaging portion in operative position and permit rocking

movement of the guard, the ends of the slots 10 coöperating with the edges of the arms to prevent relative forward and rearward movement of the nose-engaging portions with respect to the lenses.
